CLAIM

I claim the ornamental design for a barbecue grill with crank wheels, as shown and described.

DESCRIPTION

FIG. 1 is a perspective view of a barbecue grill with crank wheels showing my new design with the front door in a closed position;

FIG. 2 is a perspective view thereof with the front door in an open position;

FIG. 3 is a front elevational view of FIG. 1;

FIG. 4 is a rear elevational view thereof;

FIG. 5 is a left-side elevational view of FIG. 1, the right-side elevational view being a mirror image thereof;

FIG. 6 is a top plan view of FIG. 1; and,

FIG. 7 is a bottom plan view of FIG. 1.

1 Claim, 4 Drawing Sheets

FIG. 2
